UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

CENTRIFUGAL AIR-COMPRESSOR.

1,159,094.

Specification of Letters Patent. Patented Nov. 2, 1915.

Application filed August 19, 1912. Serial No. 715,709.

To all whom it may concern:

Be it known that I, RICHARD H. RICE, a citizen of the United States, residing at Lynn, county of Essex, State of Massachusetts, have invented certain new and useful Improvements in Centrifugal Air-Compressors, of which the following is a specification.

This invention relates to centrifugal air compressing machines, and its object is to protect the edges of the revolving vanes from injury by rubbing against the walls of the casing in which the impeller rotates. These parts are usually fitted together with a minimum of clearance, in order to avoid leakage losses. If for any reason the impeller shaft shifts longitudinally, the edges of the vanes on one side of the impeller are liable to come into dangerous proximity to the walls of the casing and run the risk of being bent or broken by scraping along over the surface of said walls. By my invention, I provide a wearing plate of soft metal, which under the conditions mentioned, will be quickly worn away and leave the vanes free to revolve as before. The wearing plate may be applied either to the vanes themselves or to the walls of the casing.

In the accompanying drawing, Figure 1 is an axial section of a portion of a centrifugal compressor showing the vanes provided with my wearing plate. Fig. 2 is an edge view of a vane so equipped, and Fig. 3 is a top plan view on an enlarged scale of a pair of such vanes.

The compressor has the usual body 1 containing the wheel casing 2 having walls 3 between which the impeller rotates. A diffuser 4 surrounds the wheel casing with vanes 5 to guide the air thrown off from the impeller. The shaft 6 passes centrally through the wheel casing and carries the impeller, which has a web 7 carrying on each side the vanes 8. Each vane has a curved inner portion 8' to give a better hold on the air entering through the eye 9 of the casing. The remainder of the vane is preferably radial or substantially so. Along each edge of the radial portion is secured a thin strip 10 of soft metal, such as brass, lead, babbitt or other alloy, firmly fastened to the

vane by rivets 11 and projecting slightly beyond the edge of said vane and into close proximity to the wall of the casing. In case the shaft shifts axially, the strip 10 on that edge of the vane which is brought closer to the wall of the casing will come in contact with said wall, and will quickly be worn down by rubbing against said wall, without injury to the vane itself.

Inasmuch as the efficiency of the machine depends largely upon the position of the vanes on the impeller disk, and their accurate maintenance in such position, it follows that this invention is actually of considerable importance in the art, in spite of its seeming simplicity.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. The combination in a centrifugal compressor having a casing and an open sided impeller designed to run with close clearances, of a wear strip of softer material than the impeller vanes fixed to and projecting over the edges of the vanes into close proximity to, but not into contact with the side walls of the casing.

2. The combination in a centrifugal compressor having a casing and an open sided impeller designed to run with close clearances, of wear strips of relatively thin material as compared to the thickness of the vanes fastened to each side of the vanes and projecting over the outer edges thereof into close proximity to the side walls of the casing.

In witness whereof, I have hereunto set my hand this 14th day of August, 1912.

RICHARD H. RICE.
